UNITED STATES PATENT OFFICE

165,412

HOLDER FOR RACING PROGRAMS OR THE LIKE

Alex D. Bernstein and Henry William Bernstein,
New York, N. Y.

Application May 26, 1951, Serial No. 15,323

Term of patent 3½ years

(Cl. D59—3)

To all whom it may concern:

Be it known that we, Alex D. Bernstein, and Henry William Bernstein, both citizens of the United States of America, and residents of New York city, county of Kings, and State of New York, have invented a new, original, and ornamental Design for a Holder for Racing Programs or the like, of which the following is a specification, reference being had to the accompanying drawing, forming part thereof, wherein,

Figure 1 is a front elevational view of a holder for racing programs or the like, showing our new design in closed position.

Figure 2 is a rear perspective view of same in partially opened position, drawn on a smaller scale.

Figure 3 is an open plan view of the inner section thereof, drawn on a smaller scale.

The characteristic features of our design reside

in the portions shown in full lines in the drawing.

We claim:

The ornamental design for a holder for racing programs or the like, substantially as shown and described.

ALEX D. BERNSTEIN.

HENRY WILLIAM BERNSTEIN.
